UNITED STATES PATENT OFFICE.

ALBERT COOK, OF HOLYOKE, MASSACHUSETTS.

ROTARY CLEARER.

Application filed September 22, 1921. Serial No. 502,553.

To all whom it may concern:

Be it known that I, ALBERT COOK, a citizen of the United States, residing at Holyoke, Massachusetts, have invented certain new and useful Improvements in Rotary Clearers, of which the following is a full, clear, and exact description.

My invention relates to rotary clearers such as are used upon spinning and twisting machines and the like for the purpose of removing lint which is liable to be caught by and twisted into the thread or yarn so as to result in an inferior product, and has for its object to provide a rotary clearer which shall emit air to blow away the lint.

My invention further has for its object to provide a self-contained attachment which can be inserted either in a body portion specially made for it, or in an old rotary clearer of the traveling type upon making a suitable bore within its core.

The following is a description of two embodiments of my invention, reference being had to the drawings in which:

25 Figure 1 shows a transverse diagrammatic view of a rotary clearer of the traveling type lying upon the rolls of a twisting or spinning machine;

Fig. 2 is a plan view of the same;

30 Fig. 3 is a longitudinal section of a rotary clearer of the traveling type embodying my invention;

Fig. 4 is a section of the same on the line 4—4, Fig. 3;

35 Fig. 5 shows broken perspective views of three vanes removed from the clearer;

Fig. 6 shows a clearer of the nontraveling type with a portion of a similar clearer adjacent thereto, both embodying my invention in conjunction.

Fig. 7 shows a section on the line 7—7, Fig. 6;

Fig. 8 shows a section on the line 8—8, Fig. 7 and

45 Fig. 9 shows a section on the line 9—9, Fig. 6.

Referring more particularly to the drawings, 1 is a core of a rotary clearer of the traveling type, said core being of the well known mechanical form and when in use resting against the rolls 2, 3 and 4, of the spinning and twisting machine. I provide this core 1 which is ordinarily of wood, with a bore having a portion 5 adjacent to the smaller end of the cone which is of smaller diameter than the other portion so as to

form a shoulder 6. Against this shoulder rests a spider 7. At the other end of the cone is secured a plate 8. The spider 7 and plate 8 carry a shaft 9 fixed thereon and are 60 preferably connected by a housing 10 secured thereto so as to form a readily removable self-contained structure. Within the housing and mounted upon the shaft 9 are a plurality of vanes, preferably three vanes 65 11, 12 and 13 having knuckles which surround the shaft 9, the vanes being so constructed as to fit between the shaft and the internal wall of the housing so as to form partitions which shall be as airtight as is 70 compatible with free movement. The vane 13 in Fig. 3, is shown broken off for the purposes of clearness. Mounted on the housing plate 8 are three projections in the form of pins 14, 15 and 16, shown approximately 75 120° apart. The vane 11 is provided with two end grooves 17 which are spaced away from the axis of the shaft 9 at distances equal to the distances of the pins 15 and 16 from said axis. The vane 12 is provided with two grooves 18 whose radial position corresponds to the radial position of the pins 14 and 15, while the vane 13 is provided with two grooves 19 whose radial positions correspond with the radial positions of the 80 pins 14 and 16.

The pins and grooves above referred to are made comparatively small so that the grooves will not seriously interfere with the tightness of the vanes within the chamber 90 of the housing.

With the clearer as thus constructed, when the clearer revolves in the direction shown by the arrow in Fig. 4, the pin 14 will engage the vane 11 so as to lift it to the position shown whereupon it will fall by gravity toward the vane 12, which is held by gravity at this time in the downward position as shown. As the vane 11 falls it passes by the pin 16 on account of one of the grooves 95 17, and pushing the air ahead of it forces it out through the lowermost part of the spider 7 so that it is discharged through the lower part of the portion 5 of the bore in the core. As it rushes out, it blows away any lint 105 which may be in the path of the blast, producing a decided puff, which is all that is necessary for that purpose. As the clearer continues to revolve the pin 12 lifts the vane 13 which in time falls toward the vane 11, then in its lower position, passing by the pin 14 on account of one of the grooves 19:

and in a similar manner the van 12 is lifted by the pin 16 and falls so that with the construction shown, there are three puffs of air delivered for each revolution of the clearer.

5 In the form shown in Figs. 6 to 8, the internal construction is the same except that the clearer is made shorter and of cylindrical form and in two connected sections, the 10 ends of each section being provided with a series of discharge holes 20 through which the air is expelled in proximity to the supporting bearings of the rolls 2; the puffs produced thus blowing away the lint therefrom. The rolls 2 are of the ordinary form 15 having end bearings and an intermediate bearing for a hook 21 carrying a weight 22 which holds the same in position. This hook is provided with an arm 23 which surrounds 20 the connection 24 between the two clearer sections and assists in holding the clearer upon the rolls. The clearer in its central portion is preferably covered with felt, as shown at 25.

25 I preferably use the vane type of blowing mechanism for embodying my invention so as to produce the puffs above referred to, but as will be evident to those skilled in the art my invention permits of various modi-

fications without departing from the spirit 30 thereof or the scope of the appended claims.

What I claim is:

1. In a rotary clearer, the combination of a clearer body having a passage therein, and means for causing air to be discharged from 35 said passage.

2. In a rotary clearer, the combination of a clearer body having a passage therein, and means carried by the clearer for causing air to be discharged from said passage.

40 3. In a rotary clearer, the combination of a body having a passage therein, and a blowing device adapted to be actuated by the movement of revolution of said body so as to cause air to be discharged from said 45 passage.

4. In a rotary clearer, the combination of a chambered body having internal and external surfaces of revolution and a plurality of vanes mounted to revolve within the 50 chamber of said body about the axis thereof and means on said body adapted to engage said vanes, respectively, so as to lift them independently and permit them when lifted to fall one at a time so as to force air out 55 of the chamber of said body.

ALBERT COOK.
